UNDERFRAME FOR VEHICLES, ESPECIALLY
RAILWAY CARSWalter B. Dean, Narberth, Pa., assignor to The
Budd Company, Philadelphia, Pa., a corpora-
tion of Pennsylvania

Application April 17, 1945, Serial No. 588,866

20 Claims. (Cl. 105—416)

1

The invention relates to an underframe for vehicles such as railway cars and more particularly to an underframe of the type having a center sill provided with cross members for supporting the flooring and for connection with the end and side walls.

A primary object of the invention is a center sill for vehicle underframes which combines minimum weight with the ability to withstand most severe stresses and to counteract the well known tendency of center sills to bend upwardly in the middle together with the entire body when subject to severe longitudinal compression.

Another object of the invention is an end underframe adapted for the transmission of the stresses from the coupler and buffer into the adjoining portion of the body center sill without undue stress concentrations and with such distribution of the stresses contributing to the achievement of the above outlined main object.

Still further objects of the invention have to do with the simple and efficient connection between the center sill and the remainder of the underframe structure, with the connection of the latter to certain of the upstanding body walls, and with the construction and arrangement of the underframe members adjoining the center sill.

With the aforesaid and other objects in view, a main feature of the invention resides in a center sill which, contrary to the customary structures, is asymmetrically constructed in regard to a horizontal longitudinal plane passing through the geometric center line of the sill and which has a concentration of strength in its lower portion so that the neutral axis lies closer to the underside than to the upper side of the sill.

Another feature of the invention consists in an end underframe construction having means for directing the stresses exerted on the end underframe by the buffer and coupler in a downwardly inclined direction and thereby toward the strong lower portion of the adjoining body center sill.

The invention is especially adapted, though by no means restricted, for use in combination with the copending applications Serial No. 580,646, "Body for Vehicles, Especially Rail Cars" of the inventor and Serial No. 580,647, "Body Construction, Especially for Rail Cars," of R. J. Theriault, both filed on March 2, 1945. The body center sill may also be used in connection with or as part of the end underframe structure disclosed in the simultaneously filed application Serial No. 588,760 of the inventor and Albert G. Dean, on "End Underframe Construction for Vehicles, Especially Railway Cars."

2

The outlined and other objects, advantages and features of the invention will be more clearly and more easily understood from the embodiment illustrated in the attached drawing and described in the following.

In the drawing:

Fig. 1 is a small scale plan view of the main framework of a railway car underframe;

Fig. 2 is a fragmentary plan view of the complete underframe on a larger scale;

Fig. 3 is a fragmentary side elevation partly in section along line 3—3 of Fig. 2;

Fig. 4 is a fragmentary plan view of one of the end underframe structures with the adjoining portion of the body center sill, the same structure being shown in the preceding figures yet on a smaller scale and with less details;

Fig. 5 is a side elevation of the structure shown in Fig. 4;

Fig. 6 is a longitudinal section along line 6—6 of Fig. 4;

Fig. 7 is a fragmentary end elevation of one of the end sills viewed in the direction of the arrows on lines 7—7 of Fig. 2 but on a larger scale;

Fig. 8 is an inside elevation of the structure shown in Fig. 7, and a section along line 8—8 of Fig. 2 through the underframe structures on the scale of Fig. 7;

Fig. 9 is a fragmentary end elevation of the transverse sill at the vestibule partition wall and a section substantially along line 9—9 of Fig. 2 through the end frame center sill on the scale of Fig. 7;

Figs. 10 and 11 are fragmentary sections through the center sill of the end frame and through adjoining underframe parts substantially along lines 10—10 and 11—11, respectively, of Fig. 2 and on the scale of Fig. 7;

Fig. 12 is a fragmentary end elevation of the bolster beam and a section through the end frame and body center sills substantially along lines 12—12 of Fig. 2 on the scale of the preceding figures;

Fig. 13 is a large scale fragmentary longitudinal section through the non-vestibule end of the underframe substantially along line 13—13 of Figs. 2 and 14;

Fig. 14 is a fragmentary plan view of the region surrounded by line 14 in Fig. 2 on the scale of Fig. 13;

Fig. 15 is a fragmentary section corresponding to and on the scale of Fig. 13 yet of the vestibule end and taken substantially along line 15—15 of Fig. 2;

Fig. 16 is a large scale section through one of

the bolster beams and the adjoining floor and a side elevation of the adjoining center sill portions, the section being taken substantially along lines 16—16 of Fig. 2;

Fig. 17 is a fragmentary end elevation of one of the cross bearers or needle beams and a section through adjoining portions of the center sill, side sill and floor substantially along line 17—17 of Fig. 2 on a similar scale as the preceding figures;

Fig. 18 is a fragmentary transverse section on the scale of Fig. 17 through the middle portion of the underframe in a region between a bolster beam and a cross bearer, the section being taken substantially along lines 18—18 of Figs. 2, 17 and 18 and on the scale of the latter.

Fig. 19 is a section through one of the cross bearers and adjoining floor portions substantially along lines 19—19 of Figs. 2, 17 and 18 and on the scale of the latter.

The underframe illustrated in the drawing comprises: a body center sill 1; end underframes 2 and 3, each provided with a center sill portion 4 and a bolster beam 5; end cross bearers 6 and 7; a vestibule partition cross bearer 8; and intermediate body cross bearers or needle beams 9. The general arrangement of these members is clearly illustrated in Fig. 1, and the skeleton framework formed by them is structurally connected with a transversely reinforced sheet metal floor designated as a whole by the numeral 10 in Fig. 2.

It should be understood that the entire construction is substantially symmetrical with respect to the longitudinal vertical center plane, and that the end underframes are substantially identical with the exception of details incidental to the fact that the car has, as customary, a vestibule and entrance wells at one end, called hereinafter the vestibule end, but is free from such wells at the other end, called hereinafter the non-vestibule end. The description or illustration of one side of the body will serve, therefore, as description for the other side, and the figures and description of either one of the end underframes will in most cases serve for disclosing the construction of both end underframes except where the differences are specifically outlined.

The construction of the end underframes is shown in detail in Figs. 4 through 16. At first, only the unitary structure composed of the center sill portion 4 and the bolster beam 5 as well as the collision or bumper member 11 will be described, leaving the description of adjoining portions of the floor and of the cross members to a later part of the specification.

Each end underframe is welded together, preferably by electric arc welding, from a plurality of steel plates cut to appropriate size, with the exception of a few complicatedly shaped parts such as the end member 11 which are preferably castings connected by welding to the remainder of the end underframe.

The center sill portion 4 of each end underframe comprises a pair of transversely spaced vertical walls 12 reinforced along their upper and lower margins by outwardly directed flanges 13 and 14. These walls with their flanges may be constituted each by a rolled U-section—see Fig. 11. From the region of lateral brackets 15 serving for the attachment of the partition wall cross beam 8, to be described later on, the lower portions of the walls diverge outwardly toward the end of the frame; these diverging portions of the

side walls and flanges are designated, respectively, 16 and 17 (Figures 4 to 6, 8, 13 and 15). The lower marginal portions of the vertical walls 12 and 16 as well as the adjoining portions of the flanges 14 and 17 are cut away over part of their length and replaced by a welded-in angle section piece 18 of heavier gauge, the flange 19 of this angle section constituting a continuation of the flanges 14 and 17 (Figures 5, 6, 9, 13 and 15). The brackets 15 are welded to the walls and flanges 12, 16, 13 and 19 and the connection to the flange 13 is reinforced by corner gussets 20 (Figures 4, 5 and 13).

At a short distance outboard of the brackets 15 each side wall 12 and its top flange 13 are continued by an angle section member having a vertical arm or wall 21 and horizontal arm or flange 22. The inboard ends of these members are interconnected by a vertical transverse web 23 and their lower margins are connected to a horizontal plate 24 which has its lateral margins welded to the upper margins of the diverging walls 16 (Figures 4, 6, 8 and 13). On the outside of the walls 12 and 16, the plate 24 is continued inboard by fins 25 which extend across and some distance inboard beyond the brackets 15 (Figures 5, 13 and 15). A transverse angle section piece has the ends of its arms 26 and 27 welded to the upper and lower margins of the plate 23 so that its apex is on about the level of the flanges 13. The arm 26 is wider than the arm 27 and its marginal portions interconnect and form continuations of the flanges 13 and 22 (Figures 4, 5, 13 and 15). The space between the arm 26, the fins 25, the brackets 15 and the wall 23 is filled out by small plates 28 arranged in the planes of walls 12 and 21 (Figures 5, 13 and 15). Besides, the triangular structure formed by the arms 26, 27 and the plate 23 is centrally reinforced by a welded-in triangular gusset 29 (Figure 4).

The end casting 11 is a hollow section structure having its top wall 30 arranged in line with the flanges 22 and its bottom wall 31 arranged on the level of the plate 24 (Figures 5 and 6). Interior transverse webs 32 and 33 are respectively arranged in continuation of the vertical walls 16 and 21 (Figures 4, 7 and 8). The lower portion of the webs 32 are continued by inner vertical wall portions of a bow or yoke 34 (Figures 6 to 8) serving for the support of the coupler (not shown). A pair of vertical horns 35 project beyond the top surface of the casting 11 and may consist of separately manufactured pieces welded to the casting proper along the lines 36. See Figures 3 to 8 and 13 to 15. These horns 35 serve as connecting means and reinforcements for and as parts of the collision beams or posts (not shown). The end casting 11 is welded, such as by arc welding, to the walls 16, 21, 24 and to the flanges 14, 22 in plane 37 where the two structures meet (Figures 4 to 6). Brackets 38 (Figures 4 and 5) serve for the support of buffer side stems (not shown).

The top wall 26 of the angle section member 26, 21 is continued by a web or plate 39 which slopes downwardly in the direction toward the bolster beam 5 and has its side margins welded to the side walls 12. The inboard end of the plate 39 is welded to a horizontal plate 40 which interconnects the wall 12 at the level of the flanges 14 and extends in both directions slightly beyond two transverse longitudinally spaced vertical webs or bulkheads 41 inserted between and welded to the walls 12 and the plate 40. See Figures 4, 6, 9, 10, 11 and 16.

Inserted between and welded to the walls 12 and the meeting margins of the webs 26, 27 and 39 is a transverse bulkhead 42 which is reinforced by an inboard directed flange 43, the lower portions of which are connected to a pair of castings or forgings 44, one on each side (Figures 6 and 9). These members 44 which are likewise welded to the walls 12 and the reinforcing angles 18, serve as guides and abutments for the draft and buffering gear (not shown). A second bulkhead 45 is arranged inboard of the bulkhead 42 and is likewise welded to the inclined web 39, the vertical walls 12, the members 18 and to a horizontal plate 43 which latter is welded along its lateral margins to the members 18 and the walls 12 and arranged at about the level of the flanges 14. The bulkhead 45 serves as the second abutment for the draft and buffering gear. See Figures 4, 6 and 10.

The side walls 12 with their flanges 13 and 14 extend inboard a short distance beyond the bolster beam 5. As shown in Figures 5, 6 and 16, the upper portions of the walls 12 with their flanges 13 end at a considerable distance outboard of the lower portions with their flanges 14 which latter constitute on each side a rearward extension or horn designated by the numeral 47. These extensions of the side walls and their flanges are for the attachment of the body center sill 1 which will be described later on.

The webs or bulkheads 41 are arranged in line with the side walls 48 of the bolster beam 5 (Figures 12 and 16). The bottom walls 49 of the bolster halves have their inner margins secured to the flanges 14 and are consequently interconnected by the latter and the plate 40. The upper walls 50 of the bolster beam halves are attached to the flanges 13 and continued and interconnected by a top plate 51 inserted between the walls 12 and of about the same longitudinal extent as the bottom plate 40. See Figures 4, 6, 12 and 16.

The box sectional bolster beams are interiorly reinforced on each side by a web or bulkhead 52 and the connections between the side walls 48 and the top flanges 13 as well as the connection between the bottom wall 49 and the bottom flanges 14 are reinforced by welded-in corner gussets 53 and 54, respectively. The middle portions of the bolster beams are upwardly and outwardly inclined and their side walls and bottom walls are provided with large openings 55 for saving of weight and for giving access for the welding operations. See Figures 4, 5, 12 and 16.

The outer ends of the bolster beams, as shown in Figures 4 to 6 and 12, are offset and provided with an upstanding plate 56 for fitting into and connection with the side sills 57 and the adjoining side walls (not shown). The formation of the ends of the bolster beams and their connections to the side sills and to the side walls is more fully disclosed in the application Serial No. 580,647 of Raymond J. Theriault, referred to hereinbefore.

From the foregoing description of the end underframes it will have become apparent that an extremely sturdy and strong structure is achieved which, for all practical purposes, can be considered as a one-piece structure inasmuch as its component parts are firmly welded together by electric arc or similar welding.

Each end underframe structure is furthermore reinforced by a cover plate 58 for the draft gear pocket, which plate is secured by a great number of bolts 59 to the flanges 18 of the rein-

forcing members 18 and extends in outboard direction beyond plate or web 46.

The axes of the stresses exerted by the buffer gear and by the draft gear (not shown) are indicated respectively, by the dot-and-dash lines 59 and 60 in Figure 6. These stresses are transferred into the walls 12 and, by means of the bulkheads 42 and 45 in collaboration with the inclined web 39 downwardly into the lower portion of the end underframe near the bolster beam. The purpose of this downward direction of stresses will become apparent from the following description of the construction of the body center sill 1.

15 The body center sill 1, as shown in Figures 12 and 16 to 19, consists mainly of two transversely spaced vertical walls 61 and a bottom wall 62. The side walls are channel sections, each having vertical web 63 and upper and lower marginal outwardly directed flanges 64 and 65. The webs 63 are stiffened each by an inwardly projecting channel section groove 66. The bottom wall 62 consists of two super-imposed plates 67 and 68. The plate 67 has marginal upwardly directed flanges 69 which overlap and are secured, such as by electric spot welding, to the webs 63 of the side walls below the channels 66. The lower plate 68 underlies and is secured, such as by electric spot welding, to the arms or flanges 65 of the side walls and the web of plate 67. Both plates 67 and 68 are provided with an upwardly projecting stiffening channel section portion 70.

Disregarding the sheet metal flooring 10, which 35 will be described later on, the body center sill 1 presents an open-top box or hollow section with a heavily reinforced bottom wall 62. The consequence of this construction is, as shown in Figure 6, that the horizontal neutral plane of the sill, indicated by the dot-and-dash line 71, lies far below the horizontal plane, indicated by the dot-and-dash line 72, passing through the geometric center of the sill. In the illustrated embodiment, the neutral plane 71 is at about $\frac{1}{3}$ of the height of the center sill. In a practical embodiment of a full size car the height 73 of the sill is 15.4" and the distance 74 from the neutral axis 71 is located at 10.82" from the top, that is, from the upper surface of the flanges 64.

50 The ends of the body center sill 1 fit telescopically between the inboard extensions of the side walls 12 and over the outsides of the top and bottom flanges 13 and 14 of the end underframes. The webs 63 and the bottom flanges 65 with the marginal portions of the reinforcing plate 68 are connected by rivets 75 and 76 to the overlapped portions of the end frames. The connection between the upper flanges 13 and 64 will be described after the description of the flooring. The 55 underside of the bottom plate 68 is overlapped at each end by a center bearing casting 77 which is connected to the plate 68 and to the flanges 14 and 65 by rivets 78. See Figures 4 to 6, 12 and 16. The center plate serves, as usual, for the connection between the underframe and the trucks (not shown).

The transverse bearers or needle beams 9, best 70 shown in Figures 17 and 19, are of closed box sectional construction having longitudinally spaced side walls 79 provided with flanges 80 along their lower margins, a bottom plate or web 81 interconnecting and secured to the flanges 80, and a channel section closing member 83 on each side of the center sill bridging by its web 84 the 75 space between the walls 79 and secured by its

arms 85 to the insides of the latter. The side walls end at the outside of the center sill and are secured to the webs 63 thereof by flanges 86. The bottom plate 81 extends across the center sill from one side of the body to the other and is secured to the flanges 85 and the bottom plate 88 thereof. The intersection of the cross bearer and the center sill is further reinforced by a pair of channel section members 87 which are secured by their bottom walls to the margins of the plate 81 and thereby to the flanges 80 and in their middle portion to the plates 67, 68 and the flanges 85.

Shear webs or bulkheads 88 are inserted between the upper portions of the center sill side walls 63 in line with the side walls 79 of the cross bearer and are secured to the center sill side walls 63 by their marginal flanges 89 (Figures 17 and 19). The space between the two plates 88 and between the inner ends of the cover plates 83 is bridged by a channel section member 90 which is similar in cross section and arrangement to the cover plates 83. It may be noted here that the cover plates 83 and 90 are not considered main stress transmitting elements of the structure but that the upper chord of the cross bearer is mainly formed by parts of the adjoining floor structure which will be described shortly hereafter.

The outer ends of the cross bearers are each closed by a vertical plate 91 which extends upwardly beyond the top surface thereof and the walls of the cross bearers are offset so as to fit into the side sills 57 (Figure 17). This end construction and the connections of the cross bearer with the side sills and with the side walls of the body (not shown) are more fully disclosed and form the subject matter of the application Serial No. 580,647, Raymond J. Theriault, repeatedly referred to hereinbefore.

The floor between the cross bearers and between the cross bearers and the bolster beams is constituted by a multitude of transversely arranged channel section members 92 having their bottom walls 93 arranged in one plane and their side walls 94 abutting and connected with each other by spot welding and provided with inturned marginal flanges 95. A few of the floor pans, as at 96, face downwardly. See Figures 2, 3, 12, 16 and 19. The pans 96 have their side walls connected with the adjoining side walls of the pans 92 and their bottom walls and flanges arranged respectively in the planes of the flanges and bottom walls of the floor pans 92. The connection between the upturned and downturned floor pans 92 and 96 is additionally reinforced by welded-on strips 97 (Figure 16). The purpose of the open-bottom floor pans is to make room for pipe lines and the like.

At some locations the side walls of adjacent floor pans are slightly spaced from each other, see at 98 in Fig. 3; and have their top flanges or walls connected by strips or bands similar to the strips 97, this spacing may serve for the insertion between the juxtaposed side walls of downwardly extending braces as suspension means of accessories (the braces and accessories are not illustrated).

The bottom walls 93 of the open-top floor pans 92 and the flanges 95 of the open-bottom floor pans 96 rest on the top flanges 64 of the center sill and are secured to the latter together with reinforcing strips 99, preferably by electric spot welding, Figs. 16, 18 and 19. Where the floor pans overlap the inward portions of the end underframes, rivets 100 pass through the re-

inforcing strips 99, the bottom wall 93 of the floor pans, the flanges 64 of the body center sill and the top flanges 13 of the end underframe, as clearly shown in Figs. 12 and 16.

5 The floor pans 92 adjoining the cross bearers 8 have their side walls 94 secured to the side walls 79 of the cross bearer and are reinforced by channel section members 101 which nest into the channel formed by the bottom wall 93, the side wall 94 and the flange 95 of the floor pan. The members 101 are also firmly secured to the floor pan and thereby to the cross bearer side walls 79. See Figures 17 and 19. These floor pans with their reinforcements 101 extend over the 10 entire width of the body underframe and constitute the main top chord members of the cross bearers rather than the cover members 83, 88 within the cross bearer, a fact briefly mentioned hereinbefore.

20 The outboard floor pans 92 abut with their outboard side walls 94, the inboard side walls 48 of the bolster beams and are secured thereto. For the latter purpose, a reinforcing band 101' is spot welded to the inside of the end side walls 94 and both are plug welded to the bolster wall 48. See Figures 12 and 16.

25 The regions between the bolster beams 5 and the vestibule partition bearer 8 or the brackets 15 at the non-vestibule end are bridged by Z-section transverse members 102 having one of their arms 103 overlappingly secured to each other and by rivets 104 and reinforcing strips 105 to the top flanges 13 of the center sill portions of the end underframes whereas their webs 106 are upwardly directed and have their top arms 107 arranged in one plane with the top flanges 95 of the channel section floor pans 92. The members 102 adjoining the bolster beams have a second upturned arm 108 (Figure 16) reinforced by a strip 101' and abutting and secured to the outboard wall 48 of the bolster beam in the same manner as described in the preceding paragraph for the inboard side of the bolster beam. The outboard member 102, Fig. 13, has its top flange turned inboard rather than in the outboard direction as the other members 102.

30 The members 102 are preferably of substantially heavier gauge than the floor pans 92, 98 so as to materially reinforce the end portions of the car which have to carry heavy equipment such as air conditioning equipment, toilet facilities, etc. The ratio in thickness may be for instance about 2 to 1. No effort has been made to show this difference of gauge in the drawing.

35 At the non-vestibule end of the underframe (Figures 8, 13 and 14) four short open-top floor pans 109 are inserted between the web or arm 106 of the last member 102 and the inboard vertical wall 110 of the end cross bearer 7. The inner ends of these short floor pans 109 are supported on each side by the outwardly extending horizontal arm 111 of Z-section plates 112, the other arm 113 of which rests on top and is secured to the respective flange 22 of the end underframe. The 40 ends of the plates 112 are secured respectively to the outboard member 102 and the inboard part 114 of the top wall of the cross bearer 7. The connection between member 112 and the floor pans is further strengthened by strips 113' secured to the outer margin of the arm 113 and the inner ends of the top flanges of the floor pans.

45 Each cross bearer 7 consists in addition to the walls 110, 114, just described, of an outer top wall portion 115, an outer wall 116 and a bottom wall 117, all of which members are overlappingly se-

cured together so as to form a closed box sectional structure (Figures 13 to 15). The inner ends of the walls 114 to 117 are reinforced by plates and channel sections 118 and 119 spot welded to the insides of these walls and are welded at 120 to the end wall 121 of the casting 11. The top wall portion 114 and the inner wall 110 overlap the top wall 30 and the inner wall 122 of the casting 11 and are secured thereto by plug welds 123, 124 (Figures 8 and 14). A transverse reinforcing and attachment strip 125 of angle section is secured to the top wall portion 114.

The construction of the sill 6 at the vestibule end is identical with the construction of the sill 7, except that it has no floor pans 109 secured thereto, so that the same reference numerals are applied to sill 6 in Figure 15 and no further description thereof is required.

The partition 8 has a wall 126 (Figures 9 and 15) together with its vertical hat section reinforcements 127 riveted to the brackets 15 and is secured by welding to the outboard web 128 of the last floor member 102. The wall 128 is slightly higher than the webs 106 of the adjoining floor members and it has its marginal flange 129 turned inboard and connected with a Z-section strip 130.

Two hat sections 131 are arranged longitudinally at both sides of the longitudinal middle plane of the body, and two other angle section members 132 are arranged close to the side margins of the underframe. The members 131 and 132 extend from the end sill 7 and its strip 125 (Figures 8 and 13) to the strip 130 at the partition structure 8 and are secured by their flanges or one of their arms respectively to the tops of the floor pans as well as on the wall portions 114 and 130 of the transverse members 7 and 8. The floor boards (not shown) extend between the members 131 and between the members 131, 132.

The opening between the walls 21 near the outboard ends of each end underframe is closed, as shown in Figures 7 and 8, by a removable plate 133 so as to give access to the chamber formed by the walls 21, the transverse web 23 and the horizontal wall 24 and serving for housing the buffer gear (not shown). The center stem and the side stems of the buffer gear project through the openings 134 and 135, respectively, of the end casting 11. The longitudinal members 136 bolted to the walls 21 serve for guiding the middle part of the buffer gear.

The outer ends of the floor pans 92, 96, 102 and 109 fit telescopingly into and are secured to the walls of the upper channel section portion of the side sills 57 (Figures 8 and 11) as is more fully disclosed in the hereinbefore cited applications Serial No. 580,646 of the present applicant and Serial No. 580,647 of Raymond J. Theriault. The side walls 57 extend uninterruptedly between and are secured to the non-vestibule end sill 7 and the partition wall structure 8 (Figures 1 and 2). The regions between the one bolster beam 5 and the end sill 7 and between the other bolster beam 5 and the partition structure 8 are reinforced by downwardly facing channel sections 137 which have their bottom walls secured to the undersides of the floor pans, their outer walls to the side sills 57 and their inner walls to an angle section strip 138. The ends of these members 137 are secured to the respective bolster beams 5 and cross bearers 7 and 8. See Figures 1, 8, 11 and 12.

While the body center sill 1 is illustrated and described in combination with substantially identical arc welded end underframes 2 and 3, different end underframes on one or both ends may be

employed. One such modified end underframe construction is disclosed in the, before mentioned, simultaneously filed application Serial No. 588,760 of the present applicant and Albert G. Dean on "End underframe construction for vehicles, especially railway cars."

It is pointed out in the beginning of this description that the end underframes are mostly formed of steel plates arc welded together and by an end casting 11. The remainder of the disclosed construction is formed practically throughout of sheet metal parts connected with each other by spot welding. The arc welds are conventionally diagrammatically indicated. The spot welds also are indicated at many places by asterisks or, in sectional views, by heavy black dots at the interfaces. The sheet metal of the construction is preferably of the high tensile type and more specifically cold rolled stainless steel.

With the full illustration and description of one embodiment of the invention in mind, the main feature of the invention, mentioned hereinbefore, will be easily understood.

The tendency of center sills to bend upwardly together with the remainder of the body under compression loads may be attributed to the fact that the loads are mostly applied near the underside of the body by the buffer and coupler, see lines 59 and 60 (Figure 6), causing compression of the center sill and the lower portion of the body whereas the upper portion of the body (not shown) is subjected to much less compression forces and is consequently less shortened. The obvious consequence of this condition is that the body will arch upwardly in its middle portion. Customarily center sills which have their neutral plane approximately coincided with the horizontal transverse plane passing through the geometric center of the sill have no remedying effect on this situation.

The new center sill construction, however, with its great concentration of strength in the lower portion of the sill effectively counteracts the tendency to arch or bend upwardly, because it requires much more strength to compress the lower portion of the sill and thereby to shorten it than to compress the upper portion thereof.

In this connection it is worth mentioning that the floor pans, though forming main transverse structural elements for the entire underframe and also between the center sill side walls, are believed to have, partly on account of the transversely extending reinforcing grooves 139 (Figures 16 and 18), no great strength in longitudinal direction so that the center sill is indeed practically an open-top box or hollow section structure. The bottom chord of this structure which is formed by the plates 67, 68 and the flanges 65 has many times the strength of the top chord constituted merely by the flanges 64 (Figure 18).

It will now also be easily understood how important it is that the stresses originating at the buffer and the buffing gear are transmitted, without abrupt change in direction, downwardly in inboard direction which is partly achieved by the inclined webs 39 and the bulkheads, bottom reinforcements and other transverse members such as 24, 26, 27 secured to the side walls 12 of the end underframes. In this same connection it will be understood why the connection between the end underframes and the lower portion of the body center sill is so much stronger

and includes a greater number of rivets than the connection near the upper margin of the body center sill.

The foregoing description and the attached drawing of one embodiment is by way of illustration only and is not intended to limit the scope of the invention as defined by the attached claims, the invention is susceptible of many modifications and of adaptations to specific body constructions without departing from its spirit and basic principles, and certain features of the invention, such as for instance the body sill or the end underframe constructions may be used advantageously independently of other features.

What is claimed is:

1. In a vehicle body, an underframe having a longitudinal center sill of such asymmetrical construction that its horizontal neutral plane is a considerable distance below the middle of the sill's height, which sill is structurally connected substantially throughout its length along its upper side to a shear panel structure of great transverse but little longitudinal stiffness.

2. In a vehicle underframe: such as for railway car bodies, a longitudinal center sill having two transversely spaced side walls and a bottom wall but being substantially open at the top so that its neutral plane is closer to the sill underside than to its upper side, and a transversely reinforced panel closing the open top and structurally connected to the upper margins of the sill's side walls substantially throughout their length, the structure having great strength against transverse stresses and counteracting the tendency of the sill and of the remainder of the body connected therewith to buckle upwardly under heavy compression stresses.

3. Underframe for vehicle bodies such as railway car bodies comprising between its wheel supported points a hollow section open-top longitudinal center sill and a transversely reinforced panel, constituting the floor supporting structure, structurally connected to the upper margins of the sill's side walls and extending across the mouth and over at least a major part of the length of the sill.

4. Underframe center sill for vehicles such as railway cars consisting mainly of two heavy gauge channel section transversely spaced longitudinally extending side wall members, of a heavy gauge bottom wall structure extending between and connected to the lower marginal arms of the side wall members, and of a light gauge top wall structurally interconnecting and interbracing said side walls, so that the closed box-sectional structure formed by said walls has its horizontal neutral plane substantially below the middle of its height.

5. A center sill for vehicles of open-top hollow section having laterally facing transversely spaced U-section side walls and a first bottom wall member overlappingly attached to and interconnecting the lower arms of the side walls, in combination with a generally U-section second bottom wall member extending between and having its arms secured to the lower portions of the webs of the side walls and its web secured to the middle portion of said first bottom wall member.

6. In an underframe for vehicle bodies, such as railway car bodies, a longitudinal center sill having supporting points widely spaced from each other in the longitudinal direction of the sill, said sill comprising two transversely spaced longitudinally extending side walls, a longitudinally ex-

tending bottom wall structurally interconnecting the side walls and a transversely stiff but longitudinally weak structure extending across the mouth of the sill and structurally interconnecting the upper margins of the side walls.

7. End underframe for vehicle bodies especially railway cars comprising a center sill portion having transversely spaced upstanding side walls interconnected by transverse webs, one of said webs 10 extending from a point near the upper side and the outboard end of the center sill portion at a gentle slope in inboard direction to a point near the underside of the center sill portion so as to direct compression forces exerted on the center 15 sill near its outboard end toward the underside of the sill.

8. End underframe for railway cars comprising a center sill portion and a bolster beam integrally connected to the center sill portion at a distance 20 inboard from the latter's outboard end, said center sill portion being provided with means for directing longitudinal impact stresses exerted on the center sill in a downwardly inclined direction toward a point of the center sill near the bolster beam.

9. End underframe for railway cars comprising a hollow section center sill having transversely spaced side walls interconnected by transverse walls and webs, the outboard end of said sill being 30 widened and provided with a top plate for the accommodation of a buffer suspension, said top plate near the outboard end of the center sill merging into a downwardly and inboard sloping web extending between and secured to the side 35 walls and approaching the underside of the side walls near the attachment zone of a bolster beam.

10. Center sill construction for vehicles provided at its end portions with means for the attachment of buffing and draft gear, in combination 40 with a middle portion adjoining the end portions, which middle portion has its horizontal neutral plane arranged below its geometric longitudinal middle line, and means on said end portions adapted for directing at least a large part 45 of the stresses exerted by the buffing and draft gear without abrupt change in direction downwardly and inboard into the lower part of the middle portion of the center sill.

11. In an underframe for railway car bodies 50 and the like, a center sill having a thick walled end portion and a thin walled sheet metal middle portion, said middle portion having such asymmetrical construction that its horizontal neutral plane is below the middle of the height of this 55 portion, the inboard end of the end portion overlapping and being secured to said middle portion for a greater length near the bottom of the sill than near its top.

12. In an underframe for railway car bodies 60 and the like, a center sill having a thick walled end portion and a thin walled sheet metal middle portion, said middle portion having such asymmetrical construction that its horizontal neutral plane is below the middle of its height, the inboard 65 end of said end portion of the center sill extending at the bottom a considerable distance further inboard than the top and overlapping the outboard end of the middle portion of the sill, and connecting means between the overlapping portions arranged near the top and bottom of the sill and extending over a greater length near the bottom.

13. Center sill structure for railway cars and 70 the like comprising at least one vertical wall provided with a laterally projecting web sloping

downwardly in inboard direction, buffing and draft gear abutments arranged beneath said transverse sloping web and secured thereto as well as to said vertical wall.

14. In an end center sill for underframes of railway cars and similar vehicles, longitudinally extending and transversely spaced side walls interconnected by an inboard and downwardly sloping web, a transverse bulkhead arranged beneath said web and secured to the same as well as to said side walls, a bottom plate interconnecting the lower margins of the side walls in the region of and secured to said bulkhead, said side walls, web and bulkhead constituting together a pocket for a buffing and draft gear and said bulkhead being adapted to serve as abutment for the buffing gear, and a removable cover plate structurally connected to the side walls, extending in outboard direction beyond said bottom plate and constituting a main stress transmitting element of the center sill structure.

15. End underframe for vehicle bodies especially railway cars comprising a center sill portion having transversely spaced upstanding side walls interconnected by transverse webs, one of said webs extending from a point near the top at the outboard end of the center sill portion at a gentle slope in inboard direction to a point near the underside of the center sill portion so as to direct compression forces exerted on the center sill near its outboard end toward the underside of the sill and to interbrace the side walls of the sill, the inboard margin of said web merging into and being secured to a generally horizontal plate which extends inboard beyond said web and is secured to said side walls.

16. In a center sill for railway cars and the like, a pair of transversely spaced longitudinal side walls constituted mainly by rolled U-sections, part of the vertical web and one arm of each U-section being cut out along part of the length and near the lower margin of the sill and replaced by an angle section member of heavier gauge, one arm of which member is welded along its margins to the margins of the cut-out of the web whereas its other arm has its ends welded to and arranged in continuation of the adjoining portions of the lower arm of said rolled sections.

17. Center sill for railway car and the like vehicle bodies, having two transversely spaced longitudinally extending upright side walls interconnected by a transverse generally longitudinally extending web and by a transverse structure generally triangular in side elevation arranged outboard of the end of said web, said structure having its one side arranged substantially vertically with its middle at about the height of the outboard end of said web and being adapted as abutment for compression transmitting means and its other two sides converging inboard upon and secured to the end of said web.

18. Center sill for railway car and the like ve-

hicle bodies, having two transversely spaced longitudinally extending upright side walls interconnected by a transverse generally longitudinally extending web and by a transverse structure generally angle shaped in side elevation arranged outboard of the end of said web, said structure having its apex arranged at the height of and secured to the outboard end of said web and its two arms diverging outboard upwardly and downwardly respectively, the outboard ends of said arms merging into generally horizontal longitudinally extending vertically spaced webs secured to and reinforcing said walls outboard of said structure.

19. In an end center sill for underframes of railway cars and similar vehicles, longitudinally extending and transversely spaced side walls interconnected by a web sloping at least over part of its length in downward and inboard direction, a transverse bulkhead arranged beneath said web and secured to the same as well as to said side walls, a bottom plate interconnecting the lower margins of the side walls in the region of and secured to said bulkhead, said side walls, web and bulkhead constituting together a pocket for a buffing and draft gear and said bulkhead being adapted to serve as abutment for the buffing gear, and a removable cover plate structurally connected to the side walls, extending in outboard direction beyond said bottom plate and constituting a main stress transmitting element of the center sill structure.

20. In an end center sill for underframes of railway cars and similar vehicles, longitudinally extending and transversely spaced side walls having their upper portions over at least a part of the length of the sill interconnected by a transverse web, a transverse bulkhead arranged beneath said web and secured to the same as well as to said side walls, a bottom plate interconnecting the lower margins of the side walls in the region of and secured to said bulkhead, said side walls, web and bulkhead constituting together a pocket for a buffing and draft gear and said bulkhead being adapted to serve as abutment for the buffing gear, and a removable cover plate structurally connected to the side walls and to said bottom plate and constituting a main stress transmitting element of the center sill structure.

WALTER B. DEAN.
